UNITED STATES PATENT OFFICE.

LEE E. JILLSON, OF HARTFORD, AND ELIJAH WILLIAMS, OF NEW HAVEN, CONNECTICUT.

BOILER-TUBE CLEANER.

1,275,437.

Specification of Letters Patent. Patented Aug. 13, 1918.

Application filed July 12, 1917. Serial No. 180,190.

To all whom it may concern:

Be it known that we, LEE E. JILLSON and ELIJAH WILLIAMS, citizens of the United States, residing at Hartford and New Haven, respectively, in the counties of Hartford and New Haven, respectively, and State of Connecticut, have invented certain new and useful Improvements in Boiler-Tube Cleaners, of which the following is a specification.

10 This invention relates to what we shall for convenience term a boiler-tube cleaner, the object of the invention being to provide a simple and effective article of this character which in operation will effectually remove 15 all particles which adhere to the inside of tubes in water-tube boilers.

In the drawings accompanying and forming part of the present specification we have shown in detail one convenient form of embodiment of the invention which will be set forth fully in the following description to enable those skilled in the art to practice the invention. We do not limit ourselves to this 25 particular disclosure; we may depart therefrom in several respects within the scope of the invention defined by the claim following said description.

Referring to said drawings:

Figure 1 is a side view of a cleaner involving the invention showing the same in a tube, the arrow indicating the direction of motion of the head.

Fig. 2 is an end elevation of the cleaner as seen from the right in Fig. 1.

Figs. 3 and 4 are cross sections on the lines 3—3 and 4—4 respectively of Fig. 1, looking in the direction of the arrows applied to the respective lines.

Like characters refer to like parts throughout the several views.

As may be inferred from the observations already made, a cleaner involving the invention is susceptible of advantageous use in various connections, although it is of particular utility however, in the cleaning of tubes, being adapted to effectually and thoroughly remove deposits which adhere to the walls or inner surfaces thereof. In Fig. 1 we have shown in section a boiler tube as 2, the

50 cleaner in this particular view being inclosed by the tube. Said cleaner involves in its make-up a body as 3, which is longitudinally tapered, an element of importance, as thereby and owing to the peculiar mounting of the cleaner-members, we are enabled to thoroughly remove deposits within a tube

such as 2. The body tapers from its head toward its tail or foot end, the head in the present case being the large end. Fitted against the head or large end of the body 3 is a plate or disk as 4, this plate or disk constituting a support or thrust bearing for the shafts or pins which carry the cleaning members hereinafter more particularly described. The plate 4 is held to the head end of the body 3, for instance by the threaded shank 5 provided with an enlarged portion or hub 6. The disk or plate 4 as shown is centrally perforated to comparatively freely receive the shank 5 which is threaded into the head portion of the tapered body 3, the boss or hub 6 fitting flatwise against the plate or disk to securely hold the same in position. This boss or hub 6 as shown is interiorly threaded to receive the reduced extension 7 on the forward end of the shaft 8 which shaft is generally rotated by some suitable power ordinarily an air driven motor to turn the cleaner in the tube. The diameter of the disk or plate 4 is approximately equal to the internal diameter of the tube, although this may not in all cases be necessary. The rear reduced end of the body 3 is engaged by a plate as 9 which is centrally perforated to receive the screw or threaded stud 10 extending from the small end of the body 3. As shown this threaded stud or screw 10 which is ordinarily integral with the body 3 fits the internally threaded opening in the practically spherical head 11 which when in operative position abuts flatwise against the rear small end of the tapered or frusto-conical body 3. This head 11 has upon it the fin 12, the outer surface 13 of which is upon a back bevel to present a cutting edge. The spherical head 11 in addition to the fin 12 is furnished with the lugs or ears 14 diametrically opposite each other and midway between the base portion of the fin 12. The lugs or ears 15 also have cutting edges 16. The result is that on the turning of the cleaner in a tube, the head 11 with its adjuncts already described will loosen up the mass adhering to the wall of the tube so as to allow its removal or detachment by cleaning members.

The frusto-conical or forwardly tapered body as shown has a chamber 15' therein, which virtually extends for the length of the body. Connecting the chamber 15' with the periphery of the body are the radial slots 110 or ways 16', there being three of such ways or slots, although this is in all cases not neces-

5 sary. Set in the slots or ways 16' are the pins 17, there being obviously three of such pins. The end portions of the pins are disposed in slots elongated radially of the body 3. From this it will be clear that the pins 17 can move bodily or float in the respective pairs of slots 18. It will be understood that the terminals of said pins 17 fit against the plates 4 and 9 already described, although 10 the engagement is not sufficient as to prevent ready movement of the pins as they should accommodate themselves automatically to the sediment being removed. Each pin carries a group of toothed wheels 19, the 15 wheels being individually freely rotative on the respective pins 17 and extending practically from the ends of the chamber 15 or which is the same thing, the ends of the respective slots 16. Each of the wheels 19 20 has a multiplicity of teeth, and one or more of the teeth project at all times beyond the periphery or circumference of the longitudinally tapered body 3. In action the cleaner will be introduced in a tube and advanced toward the right in Fig. 1, the body 25 3 as is understood and necessarily the head 11 connected therewith, being rotated in the direction of the arrow applied to the shaft 8 in said Fig. 1. As the body turns the 30 knives or cutters 12 and 14 cut into the matter which adheres to the wall of the tube and preliminarily loosen up or disintegrate the same so as to render the tube capable of being more readily and easily subsequently cleaned 35 by the pointed toothed wheels or cutters 19.

As the body 3 rotates, these cutters cut into the mass adhering to the wall of the tube and effectually dislodge the same.

There is an advantage in having the body of the cleaner on a taper, as owing to this 40 circumstance the scale is cut on a taper.

What we claim is:

A cleaner comprising an elongated externally tapered and internally chambered body, the chamber of which is unobstructed, 45 said body having slots leading from the chamber and extending to the periphery thereof, groups of independently rotative toothed cleaning members, independent shafts on which the groups of cleaner members are respectively mounted, the shafts extending longitudinally of the body and converging forwardly on lines agreeing approximately with the angularity of the taper of the body, each of said shafts being movable transversely of the body at both ends thereof and the cleaner members being located practically wholly within the body and their toothed portions extending a short distance across the periphery thereof. 60

In testimony whereof we affix our signatures in the presence of witnesses,

LEE E. JILLSON.

ELIJAH WILLIAMS.
